UNITED STATES PATENT OFFICE.

EUGENE W. SMITH, OF CHICAGO, ILLINOIS, ASSIGNOR OF ONE-HALF TO HENRY N. HUDSON, OF CHICAGO, ILLINOIS.

CORE-CHAPLET.

1,027,673.

Specification of Letters Patent. Patented May 28, 1912.

Application filed April 11, 1911, Serial No. 620,498. Renewed April 11, 1912. Serial No. 690,045.

To all whom it may concern:

Be it known that I, EUGENE W. SMITH, a citizen of the United States, resident of Chicago, in the county of Cook and State of Illinois, have made a certain new and useful Invention in Core-Chaplets; and I declare the following to be a full, clear, and exact description of the same, such as will enable others skilled in the art to which it appertains to make and use the invention, reference being had to the accompanying drawings, and to letters or figures of reference marked thereon, which form a part of this specification.

Figure 1 is a central longitudinal section, partly broken away of a molder's flask and core, having my invention applied thereto. Fig. 2 is a cross section of a molder's flask and core, having the invention applied thereto. Fig. 3 is a detail perspective view of the invention. Fig. 4 is a detail end view of the same. Fig. 5 is a detail side view of the same. Fig. 6 is a detail plan view of the same. Fig. 7 is a detail perspective view of a form of the invention having curved bearing portions at one side thereof. Fig. 8 is a detail end view of the same.

The object of the invention is to provide, in the molders' art, a chaplet or anchor device of superior character and economic structure, and the invention consists in the novel construction and combinations of parts, as hereinafter set forth.

In the accompanying drawings the letter *a*, designates an ordinary molder's flask, consisting of the drag *b*, and the cope *c*. The mold portions *d*, within these parts are shaped to provide the matrix, the wall of which is indicated at *e*. Within the matrix, when the casting is to be hollow, is supported the core *f*, in such wise that its wall is separated from the matrix wall by the proper interval to allow for the thick mass of the casting wall. The purpose of the chaplet or anchor device is to support the core in the matrix, and, to that end, a sufficient number of these devices are adjusted between the matrix surface and the wall or surface of the core, in different places about the core, so that it will be held securely in position. And while the shapes of matrices and cores are of great variety, their surfaces are nevertheless made up of plane portions, curved portions, or plane and curved por-

tions, and as the surface wall of the core is designed to be so far as practicable parallel to the surface of the matrix, the chaplets, which are of comparatively small size, can be provided in sufficiently different shapes to meet the conditions involved. Furthermore the chaplet herein provided is designed to have considerable flexibility lengthwise, while transversely, or in the direction of its thickness, it is quite stable or stiff.

The chaplets are indicated at *g*. Each of these consists of a narrow, thin strip or ribbon of metal, preferably tin or tinned sheet metal, having beveled ends, which is bent into the form of a flattened spiral of several substantially equal and parallel whirls, having the general outline of a parallelogram. Each whirl of the helix or spiral consists of two oblique bars or bearing portions *h*, *k*, of different angular directions, and two short end portions or strut bends *m*, designed to extend between the core surface and matrix wall and to sustain the pressure required to hold the core in position. The bearing portions *h*, *h*, and *k*, *k*, of the chaplet are usually of plane character, being designed respectively to coincide in planular relation so as to provide flat bearings for the sand surface and the core surface. Between these portions extends throughout the chaplet a spiral interval *p*, which also separates the strut portions *m*. When the surfaces of the core and matrix are of curved, or curved and plane form respectively, the spiral chaplet is constructed to suit such forms, in having the oblique bearing portions of one or both of its surfaces correspondingly shaped. In all cases, however, the short strut-like end portions of each whirl are designed to have sufficient width and thickness to provide proper strength of support when several of these whirls are combined in the ribbon chaplet, as indicated in the drawings. This chaplet is of elastic nature, and yet it possesses considerable strength and stiffness to resist compression in any direction. At the same time it has flexibility, so that it is easily adjusted to position, and because of its flexibility and the separation of its whirls along the bearing surfaces, it readily accommodates itself to irregularities of surface of the core and mold; and because of the frictional engagement due to the barred arrangement of its surfaces, its bearings are rendered secure.

These chaplets are designed to be made by winding or coiling the narrow ribbon of metal around templets of various shapes, suited to the character of the work in which the chaplets are to be used.

Having described the invention, what I claim and desire to secure by Letters Patent is:

- 10 1. A molder's chaplet, consisting of a narrow flattened spiral ribbon of sheet metal, having opposite oblique bearing portions connected at their ends by short strut bends, the whirls of the spiral being separated by a continuous interval.
- 15 2. A helical chaplet consisting of a series

of flattened whirls having opposite oblique surface bearings connected by strut-like bends at their ends, and a spiral interval extending between said bearings and bends.

3. A molder's chaplet of flattened helical 20 form, consisting of a narrow metal ribbon having flattened whirls in substantially parallel position.

In testimony whereof I affix my signature, in presence of two witnesses.

EUGENE W. SMITH.
